UNITED STATES PATENT OFFICE.

EDMUND BRUDER, OF CHICAGO, ILLINOIS, ASSIGNOR TO JACOB GLOS, OF ELMHURST, ILLINOIS.

GAME APPARATUS.

Application filed April 16, 1921. Serial No. 461,761.

To all whom it may concern:

Be it known that I, EDMUND BRUDER, a citizen of the United States, residing at Chicago, in the county of Cook and State of Illinois, have invented certain new and useful Improvements in Game Apparatus, of which the following is a specification.

This invention relates to improvements in game apparatus, and one of the objects of 10 the invention is to provide an improved device of this character by means of the use of which an interesting and fascinating game may be played by rules or otherwise.

A further object is to provide an improved device of this character which will be simple, durable and light in construction, enabling the same to be used upon a table or other support and readily passed from one player to another, cheap to manufacture, and effective and efficient in operation.

To the attainment of these ends and the accomplishment of other new and useful objects as will appear, the invention consists 25 in the features of novelty in substantially the construction, combination and arrangement of the several parts, hereinafter more fully described and claimed and shown in the accompanying drawing illustrating this 30 invention, and in which—

Figure 1 is a side elevation.

Figure 2 is an end elevation.

Figure 3 is a vertical sectional view taken on line 3—3, Figure 1.

Figure 4 is a top plan view of the blank from which the supports are formed.

Figure 5 is a detail elevation of a modified form of the invention.

Figure 6 is a sectional view on line 6—6, 40 Figure 5.

Referring more particularly to the drawing the numeral 10 designates a supporting base which may be of any desired size and configuration and constructed of any suitable material. Opening through the upper 45 face of the base is a groove or slot 11, which preferably extends entirely across the base.

The numeral 12 designates generally a blank of any suitable light sheet material 50 which is shaped and bent upon itself so as to form a base portion 13 and upright portions 14—15, which are connected by the base portion 13. These uprights 14—15 may be of any desired configuration but are 55 preferably provided with openings 16—17

therein for a purpose to be set forth, and the base portion 13 is also provided with a slot 18. At the upper ends of the uprights 14—15 are bearings 19—20. The blank thus formed is bent into shape and the base or 60 connecting portion 13 is of any desired width to hold the uprights 14—15 spaced a suitable distance. The blank is provided with kerfs 21, so as to permit the uprights to be bent with respect to the base and when 65 thus shaped the base is inserted in the groove or slot 11 in the base 10. The extremities 22 of the base portion 13 are preferably rounded so as to co-incide with the periphery of the adjacent portion of the 70 base.

When thus assembled the uprights and base 10 are connected in any suitable manner preferably by means of fastening bolts 23, which pass through suitable openings 24 75 in the portion 13 and also into the base 10, preferably from the upper face thereof. The base is provided with recesses 25 opening through the lower face thereof into which the extremities of the bolts 23 project 80 and nuts 26 are threaded upon the bolts 23 to stand within the recesses 25. These recesses 25 are of such a depth that the extremities of the bolts and nuts 26 will be maintained elevated above a supporting surface. In order to enable the apparatus to 85 be moved upon a polished surface without injuring or marring the same, the base may be provided with suitable fabric 27, such as felt or the like upon the lower face thereof. 90

The numeral 27 designates generally a disc like element provided with an opening 28 at the center thereof into which opening and from opposite sides of the disc project bushings 29, which are provided with 95 rounded extremities 30 and flanges 31 at the base of the rounded portions 30. These bushings 29 are adapted to be inserted into the opening 28 from the opposite faces of the disc so that the flanges 100 31 will abut the adjacent faces and the bushings will terminate short of each other in the opening 28. Projecting through the opening 28 and also into the bushings 29, is a tubular element 32, provided with internal 105 screw threads. The ends of this tubular element terminate adjacent the crown of the portions 30, so that when the disc 27 is placed between the uprights 14—15, the rounded portions 30 will abut the inner 110

faces of the respective uprights. The disc is rotatably held in this position by means of suitable screws or bolts 33, which pass through the respective openings 19 and 20 in 5 the uprights 14—15 and are threaded into the tubular element 32. With this construction it will be manifest that the disc 27 will be supported for free rotary movement between the uprights 14—15, and may be 10 easily spun about its axis when desired.

The disc 27 is preferably enlarged as at 34 at its periphery so as to form shoulders 35, beneath which shoulders are a series of apertures 36, which preferably extend 15 entirely through the disc. A peripheral groove 37 is arranged in the disc and the diameter of this groove is somewhat less than the diameter of the enlarged portion 34, so that the groove 37 will preferably be arranged 20 centrally thereof. A plurality of transversely arranged grooves 38 are provided in the periphery of the portion 34 and communicate with the groove or opening 37.

Clip like members 39 are provided with 25 spaced substantially parallel portions 40. One of these clips is adapted to be seated in each of the grooves 38, so as to extend transversely of the groove 37, and to be spaced from the bottom thereof, with the portions 30 40 of the clip engaging opposite faces of the portion 34. The extremities 41 of the clip are deflected toward each other and are adapted to be seated in the openings 36, so that the clip will be secured in position upon 35 the disc and the groove 38 will prevent lateral displacement of the clip.

These clips are arranged any suitable distance apart and extend entirely about the periphery of the disc, and form abutments 40 as well as dividing the lateral faces of the disc into separate spaces 42.

An element 43 preferably of a flexible nature is provided with a head 44, and a pointed extremity 45. The face of the head 44 is preferably rounded as shown and is adapted to be seated in a rounded portion 46 of the groove 37, and when thus seated the body of the element 43 extends 45 through the slot 18 in the base 13, so that the extremity 45 of the element 43 will project into the groove 37 in the periphery of the disc and beyond the clip. This element 43, being held against lateral displacement by the walls of the slot 18, being maintained 50 in position when the base 13 of the uprights is anchored.

With this improved construction it will be manifest that the disc having a free rotary movement may be spun any desired 60 number of times about its axis and when so spun the portions of the clips 39 which extend across the groove 37, will successively engage and deflect the extremity 45 of the element 43 and will have an operation in the 65 nature of a ratchet across the extremity of

said element, and when the speed of rotation of the disc decreases sufficiently the extremity 45 of the elements 43 will serve as a means for causing one of the spaces 42 of the disc to assume a predetermined position with respect to the extremity 45 of the element 43.

Within the spaces 42 are arranged indicating characters of any desired type, preferably numerals and these characters are arranged preferably in a predetermined 70 number of groups, the adjacent groups being separated from each other by means of intervening characters 46—47, and which latter characters may be of a different 75 denominational nature.

The groups of characters are all preferably of the same denomination or indication and the characters of the respective groups are differentiated from the next adjacent character in any suitable manner such as by means of a different color. This may be accomplished by providing the characters 48 in each group of one color, say yellow, while the characters 49 of the same group may be 80 in a different color as red, while the intervening characters 46 may be indicated in another color as blue, and the intervening characters 47 may be indicated in still another color such as green, the letters Y, R, B, and G indicated in Figure 1 designate 85 respectively the colors yellow, red, blue and green. Obviously any other desired colors or any other arrangement may be provided.

These characters may be placed upon the opposite faces of the disc in any suitable manner such as by printing the same upon 90 paper or other element and applying it to the faces of the disc, or by placing the characters in different colors directly upon the 95 face of the disc.

In Figures 5 and 6, the lateral faces of the enlarged portion 34 of the disc are recessed as at 50, and the indicating characters may be placed within these recesses.

It is thought that the operation of this device will be clearly understood from the foregoing, but briefly stated it is as follows.

The player grasps the apparatus by the base so as to hold it steady and with one hand may spin the disc 27 upon its axis any desired 110 number of times, so that it will rotate freely about the axis and at any desired speed. As the disc rotates the clip like elements 39 will ratchet across the extremity 45 of the element 43 and when the disc stops rotating, the element 43 will stand between two adjacent clips and will indicate one or the other of the characters on the face of the disc, the result of which indication may be determined 115 by any rules adopted for the game to be played.

By the provision of the indicating characters on the opposite faces of the disc the result of the play may be seen by players who 120 may be sitting opposite to the user.

It will also be manifest that the characters on the face of the disc may be arranged in any predetermined or desired relation with respect to each other.

5. The openings 16 and 17 in the uprights 14-15 serve as a means whereby a clear vision may be had of the element 43 and space 42 which stands adjacent the element when the disc is at rest.

10. While the preferred form of construction has been herein shown and described it is to be understood that various changes may be made in the details of construction, and in the combination and arrangement of the 15 several parts, within the scope of the claims, without departing from the spirit of this invention.

What is claimed as new is:

1. A game apparatus embodying a support, a disk like element mounted upon the support for free rotation, spaced stops arranged about the periphery of the said element, portions of the stops co-operating with the lateral face of the disc for dividing said face into separate spaces, and a yieldable and fixed element projecting across the path of movement of the said stops.

2. A game apparatus embodying a support, a disc like element mounted upon the support for free rotation with respect thereto, there being a circumferential groove extending about the periphery of the disc, a plurality of elements carried by the disc, portions of the elements extending transversely of the groove, and a fixed flexible element, a portion of the element projecting into the groove beyond the portions of the first recited elements that project in a direction across the groove.

40. 3. A game apparatus embodying a support, a disc like element mounted upon the support for free rotation with respect thereto, there being a circumferential groove extending about the periphery of the disc, a plurality of elements carried by the disc, portions of the elements extending transversely of the groove, a fixed flexible element, a portion of the element projecting into the groove beyond the portions of the first recited elements that project in a direction across the groove, and indicating characters carried by the disc intermediate the adjacent first recited elements.

45. 4. A game apparatus embodying a supporting base, an upright, a lateral projection at the base of the upright and having a slot therethrough, an element disposed between the base and the said lateral projection, said element projecting through the said slot and beyond the said lateral projection, a disc like element supported by the upright for free rotation with respect thereto, and means carried by the disc and adapted to engage and flex a portion of the said element when the disc is given a rotation.

5. A game apparatus embodying a support, a disc like element mounted thereupon for free rotation with respect thereto, a fixed flexible element adjacent the periphery of the disc and with respect to which element the disc is rotatable, means circumferentially spaced about the periphery of the disc and adapted to successively engage and deflect the said element when the disc is rotated, and indicating characters carried by the disc and co-operating with the said means, the said characters being arranged in a plurality of groups, all of the groups embodying similar characters, alternate characters of each group being of a similarly indicating characteristic, the adjacent group of characters being separated from each other.

6. A game apparatus embodying a supporting base, spaced uprights formed from a single piece of sheet material bent into shape to form a connecting portion therebetween, there being a slot in the said portion, there being a recess in the base with which the said slot registers, an element seated in the recess and projecting through the slot and beyond the said portion, a disc like element supported between the uprights for free rotation with respect thereto, and means carried by the disc, spaced about the periphery thereof and adapted to successively engage and flex a portion of the said element when the disc is given a rotation.

7. A game apparatus embodying a supporting base, spaced uprights formed from a single piece of sheet material bent into shape to form a connecting portion therebetween, there being a slot in the said portion, there being a recess in the base with which the said slot registers, an element seated in the recess and projecting through the slot and beyond the said portion, a disc like element supported between the uprights for free rotation with respect thereto, and means carried by the disc spaced about the periphery thereof and adapted to successively engage and flex a portion of the said element when the disc is given a rotation, there being an open groove extending about the periphery of the disc, the said means embodying clip like elements detachably secured to the disc, a portion of the clips extending across the said groove and into which groove a portion of the said element projects.

8. A game apparatus embodying a support, a disc mounted thereupon for free rotation with respect thereto, said disc having a laterally enlarged portion adjacent its periphery, there being openings through the faces of the disc beneath and adjacent the said enlarged portion, said openings extending around the disc, clip like elements extending across the periphery of the disc, portions of the clips engaging the lateral faces of said enlarged portions, the ex-

tremities of the clips being laterally deflected and adapted to be seated in the said openings to hold the clip in position, and a fixed element with respect to which the disc 5 is rotatable, the extremity of the last said element projecting into the path of movement of the clips to be successively engaged and deflected by the clips when the disc is rotated.

- 10 9. A game apparatus embodying a support, a disc mounted thereupon for free rotation with respect thereto, said disc having a laterally enlarged portion adjacent its periphery and being provided with an open 15 groove extending about the periphery, there being openings through the faces of the disc beneath and adjacent the said enlarged por-

tions and extending about the disc, clip like elements extending across the periphery of the disc and the groove therein, portions of 20 the clips engaging the lateral faces of the disc, the extremities of the clips being deflected and adapted to be seated in the said openings to hold the clips in position, and a fixed element with respect to which the 25 said disc is rotatable, the said element projecting into the path of movement of the clips and into the said groove and adapted to be successively engaged and deflected by the clips when the disc is rotated.

In testimony whereof I have signed my name to this specification, on this 11th day of April, A. D. 1921.

EDMUND BRUDER.
